UNITED STATES PATENT OFFICE.

WALTER B. HARRIS, OF INDIANAPOLIS, INDIANA.

AIR OR GAS LIFT FOR FLUIDS.

SPECIFICATION forming part of Letters Patent No. 759,706, dated May 10, 1904.

Application filed July 6, 1903. Serial No. 164,360. (No model.)

To all whom it may concern:

Be it known that I, WALTER B. HARRIS, of Indianapolis, county of Marion, and State of Indiana, have invented a certain new and useful 5
 5 Air or Gas Lift for Fluids; and I do hereby declare that the following is a full, clear, and exact description thereof, reference being had to the accompanying drawings, in which like numerals refer to like parts.

10 The object of this invention is to provide novel means for elevating or pumping water, oil, or other fluid out of a well or the like by the use of compressed air or gas or the like.

15 The feature of this invention consists in providing a casing with a single delivery-tube therein and with a number of ejectors at intervals and independent pipes leading to each ejector, through which compressed air or gas may be forced, and also combining there- 20 with means for introducing compressed air or gas in the casing upon the body of liquid.

The full nature of this invention will be understood from the accompanying drawings and the following description and claim.

25 In the drawings, Figure 1 is a central vertical section longitudinally through the head with parts broken away. Fig. 2 is a central vertical section of the upper part of the device transversely through the head with parts 30 broken away. Fig. 3 is a section on the line 3 3 of Fig. 1.

In detail, 10 is a casing having on it a head 11, that is air-tight. A delivery-tube 12 extends from the top to the bottom of the well 35 and at the bottom is secured to the ejector 13, which carries on its intake end a strainer 14. There are ejectors 13 at intervals in said delivery-tube, and said tube is larger above each ejector than below it. In what is shown herein 40 there are three ejectors, and these are connected with three air or gas pipes 15 of substantially the same dimensions, through which compressed air or gas may be forced from any suitable supply. The pipe 15 at the

left of Fig. 1 extends to the bottom ejector 45 and lifts the fluid at least as high as the ejector above it. The pipe 15 shown at the right of Figs. 1 and 2 leads to the middle ejector and lifts the fluid therefrom to the ejector above it. The pipe 15 at the left of Fig. 2 50 extends to the upper ejector and forces the fluid therefrom out of the mouth of the delivery-tube. There are therefore three sections in this pump, each of which may be about five hundred feet long, so that the compressed 55 air entering each pipe 15 lifts the fluid about the same distance, and by having a succession of lifts the air or gas need not be introduced at a very high pressure—say a forty-five-pound pressure being sufficient. Whenever com- 60 pressed air or gas is introduced into the casing 10 through the pipe 20, so as to force down the body of fluid, it coöperates with the foregoing parts in elevating the fluid. Without compressed air or gas being forced through 65 the pipe 20 higher pressure will be needed through the pipes 15. A blow-off pipe 40 is provided at the upper end of the casing with a valve 41, so as to relieve the pressure within the casing if it becomes excessive. 70

What I claim as my invention, and desire to secure by Letters Patent, is—

An air or gas lift for fluids including an air-tight casing, a single delivery-pipe within the casing, ejectors connected with and arranged 75 in said pipe at intervals, a separate pipe leading to each ejector through which compressed air or gas may be introduced, and means for introducing compressed air or gas into said casing to press downward upon the body of 80 fluid therein.

In witness whereof I have hereunto affixed my signature in the presence of the witnesses herein named.

WALTER B. HARRIS.
